ADJUSTABLE CABLE GUIDED MEMBER FOR
LIMIT STOP WEIGHTSRichard B. Hunter, Shorewood, Wis., assignor to
Cutler-Hammer, Inc., Milwaukee, Wis., a corporation of Delaware

Application November 13, 1943, Serial No. 510,142

17 Claims. (Cl. 16—1)

1

This invention relates to improvements in adjustable cable guided members for limit stop weights.

Adjustable cable guided members of this general character are disclosed in my prior Patent No. 2,313,995, granted March 16, 1943, for Crane limit switch. Thus in Fig. 5 of said Patent No. 2,313,995 are shown a pair of hairpin type guides which are adjustable to embrace a pair of dead or non-moving cables. However, in view of the fact that said hairpin type guides are only adjustable in a straight line direction, the center line of the stop weight can register with the center line of the bracket or platform associated with the bodily movable hoist block or pulley, to which the crane hook is attached, only when the limit stop weight and the hoist block are of a given size relatively to each other and when the cables with which the hairpin type guides cooperate are in a given alignment with each other.

In practice the hoist block may have a multiplicity of cable lines associated therewith, with the dead or non-moving cables in various different positions relatively to each other according to the particular installation. As is well understood by those skilled in the art, it is very desirable that the guides may be arranged to cooperate with dead cables, in order to minimize the wearing of the cables by the guides during operation of the crane.

A primary object of the invention is to provide a reset weight wherein the associated guides are universally adjustable for cooperation with any desired pair of cables in the group.

Another object is to provide for such adjustment of the cable guided members as to insure centering of the reset weight with respect to the hoist block under all of the various conditions met with in practice.

Another object is to provide novel and simple means for effecting the desired adjustments of the cable guided members and for rigidly securing the same in their adjusted positions.

Another and more specific object is to enable assembly of the guides with respect to the cables without requiring unreeving of the latter or disassembly of the former from the reset weight.

Another object is to provide resilient guides for cooperation with the cables whereby the hammering or pounding effect of the guides upon the cables, due to vibration or swinging of the reset weight, is minimized.

Another object is to provide a special form of cable guided rods the excess lengths of which

2

may be readily removed to suit a particular installation.

Another object is to provide adjustments whereby the axes of the cable guided members may be located at any two points within a very wide range with respect to the axis or center line of the reset weight.

Another object is to minimize the number of different parts required for accomplishment of the aforementioned desirable results.

Other objects and advantages of the invention will hereinafter appear.

The accompanying drawings illustrate a preferred embodiment of the invention which will now be described, it being understood that the invention is susceptible of embodiment in other forms within the scope of the appended claims.

In the drawings,

Figure 1 is a top plan view of a reset weight having my universally adjustable cable guided members associated therewith.

Fig. 2 is a side elevational view of the device shown in Fig. 1.

Fig. 3 is a fragmentary view, partly in vertical section on the line 3—3 of Fig. 1, showing the manner in which each cable guided rod may be rigidly secured to its adjustable supporting plate.

Fig. 4 is a view, partly in vertical section on the line 4—4 of Fig. 2, showing the means for affording adjustment and effecting attachment of the supporting plates relatively to each other and to the reset weight associated therewith.

Fig. 5 is an elevational view of a crane limit switch installation having my improved device associated therewith.

Fig. 6 is a top plan view of the reset weight and cable guided members, illustrating the manner of adjusting the latter for the installation shown in Fig. 5, the contour of the hoist block being shown in dotted lines, and

Fig. 7 is an enlarged fragmentary view, partly in perspective and partly in section, of certain of the parts shown in Fig. 3.

In the drawings, the numeral 10 designates a weight which is adapted to be supported by a cable 11 (Fig. 5) from one end of a lever 12 pivoted at 13; the other end of which lever is provided with an enlargement or counterweight 14 which biases the same to its dotted line position when it is relieved of the overpowering bias afforded by weight 10. Lever 12 is adapted to control operation of a suitable limit switch mechanism housed within a casing 15; as, for example, a snap action switch mechanism like that disclosed in said Patent No. 2,313,995.

Weight 10 may be of cylindrical contour as shown, and the same is provided with a central opening or passage 16 (Fig. 4) to accommodate the shank of an eye bolt 17, the threaded lower end of which is positioned as shown within the enlarged lower end portion 18 of said passage. The enlargement or countersink 18 is preferably of rectangular form in transverse cross section to accommodate a square nut 19 into which bolt 17 is threaded; a lockwasher 20 being preferably interposed between nut 19 and weight 10. After the various parts are assembled as shown in Fig. 4 the projecting lower end of bolt 17 may be upset over nut 19, as indicated at 21, to prevent removal of the latter from the former. As best illustrated in Fig. 4, care is taken to avoid threading of bolt 17 into nut 19 to such an extent that the flange or shoulder 24 will have a clamping effect upon plates 22.

Positioned upon the upper surface of weight 10 are a pair of reversely arranged flat, punched sheet metal plates 22, 22 of identical form. Plates 22, 22 are preferably of rectangular contour, as shown in Figs. 1 and 6, and the same are respectively provided with circular openings 23, 23 (Fig. 4) which are alined in the assembled positions of said plates to freely accommodate the shank of bolt 17; the latter being provided with the aforementioned integral flange or shoulder 24 to restrain said plates jointly against substantial upward displacement from weight 10. Bolt 17 is also provided with an eye 25 for attachment of cable 11 (Fig. 5).

Each plate 22 is provided with an arcuate slot 26 (Figs. 1 and 6) which is concentric with the aforementioned opening 23 therein; said slots 26 being alined with each other throughout the length thereof when plates 22 are in their normal (or rectangularly alined) positions shown in Fig. 1. The upper surface of weight 10 is provided with a recess 27 (Fig. 4) which is preferably square or rectangular to accommodate the correspondingly shaped head 28 of a bolt the threaded shank 29 of which projects upwardly, with clearance, through said slots 26. Any other suitable form of bolt (such as a carriage bolt) may, of course, be employed if desired.

Superimposed upon the top surface of the upper plate 22 is a flat metal washer 30; a lockwasher 31 being interposed between washer 30 and a nut 32, which is adapted when tightened to clamp the plates 22 in a fixed relationship to each other. As will be understood the head 28 of bolt 29 will act under such a condition to restrain plates 22 against rotary movement jointly relatively to weight 10. However, upon loosening of nut 32 (Fig. 1) plates 22 may be adjusted angularly relatively to each other, and rotatively with respect to the shank of eye bolt 17, throughout the total range afforded by the slots 26, 26 in the plates 22. One such angular adjustment of plates 22 is shown in Fig. 6; it being understood that when the desired adjustment of plates 22 relatively to each other has been effected said nut 32 may be tightened to maintain such adjustment.

Each plate 22 is also provided adjacent its outer edge with at least two parallel pairs of relatively small circular openings, the openings of one pair being shown at 33, 34 in Fig. 3. The pairs of openings 33, 34 are adapted to accommodate the threaded shanks of U-bolts 35; the loop portions of said pair of bolts 35 being adapted to embrace the straight rod-like portions 36, 36 of resilient metal guides associated with the cables. Each plate 22 has partially embedded in a correspond-

ing surface thereof a pair of hardened steel dowel pins, one of which is shown at 37 in Fig. 3.

Said dowels 37 are positioned to underlie the loop portions of the U-bolts 35; the same having the lower cylindrical portions thereof located in drilled counterbores, as shown at 38 in Fig. 3. Said dowels are ring staked over a portion of the sharp cone-shaped upper ends thereof, as shown at 39 in Figs. 3 and 7. The threaded ends or shanks of U-bolts 35 have nuts 32 associated therewith for drawing the loop portions of said bolts against the portions 36 of the respective guides, whereby dowels 37 are pressed or forced into said portions 38 to clamp the latter to plates 22 and to prevent turning of said portions 36 with respect to said plates 22. Lock washers 31 are preferably interposed between plates 22 and nuts 32 to prevent accidental loosening of the latter. As best illustrated in Fig. 7, the ring staking involves use of a suitable tool (not shown) to upset inwardly an annular portion of one surface of a plate 22; said upset portion overlying the base portion of the cone-shaped end of a dowel pin 37 to rigidly attach the latter to plate 22.

In Fig. 1 I have shown the portions 36 of the guides extending to a substantially maximum degree from one side of the plates 22, but it is to be understood that the length or lengths to which the portions 40, 40 of the guides extend from said side of the plates may be varied as desired by merely loosening the nuts 32 associated with bolts 35, effecting the desired adjustments of portions 36 with respect to plates 22, and then re-tightening said nuts. Also it is to be understood that if desired one or both of the portions 36 of the guides may be assembled with respect to plates 22 to extend from the opposite side from that shown in Fig. 1. Also as indicated in Fig. 6, by merely loosening the nut 32 associated with bolt 29 the plates 22 may be partially rotated relatively to the eye bolt 17 and to each other, to bring the portions 40, 40 closer to or more widely separated from each other, within the range afforded by the length of said arcuate slots 26.

Inasmuch as the adjustment in the field of the various parts for a given installation will ordinarily be permanent, I prefer to peen or upset the shank ends of bolts 29 and 35 over the nuts 32 respectively associated therewith, whereby the adjustments effected will be maintained.

The portions 40 of the guides are in the form of open helices, as best illustrated in Figs. 2, 4 and 5; and as will be apparent from consideration of Fig. 5 this open form of the helices provides for effecting cooperative positioning thereof around the cables 41 and 42 without unreeving the latter from block 43. Disengagement of guide portions 40 from said cables may, of course, be effected by a reverse operation of the parts. This feature is of importance both in original installations and in the event that replacement of weight 10 or any of the parts carried thereby is required.

As aforesaid, it is desirable that the weight 10 be initially positioned and retained in centered relationship to the block 43; the latter having a bracket or platform 44 associated therewith in a known manner. Upon movement of block 43 upwardly toward a given extreme position, the platform 44 lifts weight 10 to remove the overpowering bias from lever 12, whereupon the latter is free to move under its normal bias to effect the desired operation of the limit switch mechanism. Although I have shown lever 12 as provided with a biasing counterweight 14, it is obvi-

ous that any suitable spring biasing means might be substituted for said counterweight.

As aforescribed, adjustment of the distance or distances between the vertical axis of weight 10 and the vertical axes of the respective helices 40 may be effected by loosening the U-bolts 35 and sliding the straight end portions 36 of the guides inwardly or outwardly as required. The adjustment of the angle between or lateral spacing of helices 40 is effected by loosening nut 32 on bolt 29 and rotating the guide supporting plates 22 individually to the desired degree about the vertical axis of weight 10, as represented by eye bolt 17. In the particular form of the device herein illustrated the adjustments are such that each helix 40 may be positioned at any distance varying from four and one-half inches to eleven inches with respect to the aforementioned axis of weight 10.

Inasmuch as the guides are preferably of identical form the helix 40 of one is arranged to project upwardly whereas the helix 40 of the other projects downwardly to equalize the distances of the respective cables from the center line of weight 10. However, in certain installations it may be found desirable to have both of the helices project upwardly or downwardly relatively to the top surface of weight 10, without sacrificing any of the advantages of my device, and at the same time actually increasing the range of adjustment of said parts.

As best illustrated in Fig. 1, the ends 45 of helices 40 are bent or turned outwardly with respect to the main bodies thereof to insure against likelihood of engagement thereof with the cables associated therewith. A similar result might be obtained by grinding or shearing said ends to avoid abrasion of the cables thereby.

The guides 36 are formed of a suitable resilient metal, such as steel; the resiliency thereof serving to reduce the blows upon the cables due to vibration or swinging of weight 10, thus minimizing the likelihood of cable failure due to hammering or wear. The guides are tempered to such a degree that any excess length of the straight portions 36 thereof may be removed by the use of a hack saw after the various parts have been assembled, in the event that such excess length interferes with the hoist mechanism.

As will be apparent from consideration of Fig. 5 the upper end of the weight supporting cable 11 is constrained to travel in an arcuate line (by reason of its attachment to lever 12 pivoted at 13). Hence if platform 44 is moved rapidly downwardly out of supporting relationship to weight 10 when the latter is in its upper extreme position there will be an inherent tendency of said weight to swing pendulumwise. If the helices 40, 40 surrounding the respective cables 41 and 42 were rigidly mounted with respect to weight 10 said helices would tend to hammer or pound against their respectively associated cables. A similar result would follow in the event of vibration of weight 10 from any cause. However, as aforeslated the resilient intermediate portions of the respective guides 36 act to absorb or cushion the effect upon the cables 41 and 42 of such vibration or swinging of weight 10, with the desirable results aforescribed.

As will be apparent from consideration of Fig. 1, the arcuate extent or length of slots 26 in plates 22 is preferably such that each of the helices 40 may be positioned at any desired point within an arcuate area extending through at least 90 degrees; the inward and outward adjustments 70

of portions 36 of the guides afforded by U-bolts 35 determining the width of such arcuate areas. Moreover, by providing for reversible mounting of portions 36 with respect to plates 22 the positioning areas afforded for helices 40 are doubled. The result is that said helices may be jointly located at any desired pair of points within a complete annular area, the width of which area is determined by the adjustment of portions 36 with respect to plates 22, as aforescribed.

I claim:

1. An adjustable cable guided device comprising, a limit stop weight, a pair of metal plates carried by said weight at one end of the latter, 15 a cable guided member carried by each plate, each member having a straight portion adjustable in a straight line throughout a given range relatively to its associated plate, and associated means affording rotative adjustment of said plates relatively to each other throughout a given range.
2. An adjustable cable guided device comprising, a limit stop weight, a pair of metal plates carried by said weight at one end of the latter, 20 a cable guided member carried by each plate, each member having a straight portion adjustable in a straight line throughout a given range relatively to its associated plate, associated means affording rotative adjustment of said plates relatively to each other throughout a given range,
- 25 3. An adjustable cable guided device comprising, a limit stop weight, a pair of metal plates carried by said weight at one end of the latter, a cable guided member carried by each plate, each member having a straight portion adjustable in a straight line throughout a given range relatively to its associated plate, associated means affording rotative adjustment of said plates relatively to each other throughout a given range,
- 30 4. An adjustable cable guided device comprising, a limit stop weight, a pair of metal plates carried by said weight at one end of the latter, a cable guided member carried by each plate, and each member including an end portion in the form of an open helix, the axis of which helix is arranged at a right angle to the straight portion of said member.
- 35 5. In combination, a crane limit stop weight, a pair of members each having an end portion formed to be guided by a cable and a straight portion supported in a plane at a right angle to the vertical center line of said weight, means for effecting adjustment of said straight portion axially of its length throughout a predetermined range, and associated means for effecting rotary adjustment of each member bodily throughout a predetermined range with respect to said vertical center line of the weight, for the purpose set forth.
- 40 6. In combination, a crane limit stop weight, a pair of members each having an end portion formed to be guided by a cable and a straight portion supported in a plane at a right angle to the vertical center line of said weight, means for effecting adjustment of said straight portion axially of its length throughout a predetermined range, and associated means for effecting rotary adjustment of each member bodily throughout a predetermined range with respect to said vertical center line of the weight, for the purpose set forth.
- 45 7. In combination, a crane limit stop weight, a pair of members each having an end portion formed to be guided by a cable and a straight portion supported in a plane at a right angle to the vertical center line of said weight, means for effecting adjustment of said straight portion axially of its length throughout a predetermined range, and associated means for effecting rotary adjustment of each member bodily throughout a predetermined range with respect to said vertical center line of the weight, for the purpose set forth, each of said cable guided portions being in the form of a vertically positioned open helix, whereby the same may be cooperatively assembled with respect to a cable without requiring unreeving of the latter.
- 50 8. The combination with a reset weight for a crane limit stop, of a pair of sheet metal plates supported by said weight at one end of the latter, means providing for pivotal adjustment of said plates either individually or jointly throughout a predetermined range with respect to said end of the weight, said last mentioned means including means for retaining said plates in their adjusted positions and for restraining the same against rotary displacement with respect to said weight, a member supported by each of said plates, each member comprising a rod-like portion adjustable at will in a straight line with respect to its associated plate, and each member also comprising a vertically extending open helix, said
- 55 9. The combination with a reset weight for a crane limit stop, of a pair of sheet metal plates supported by said weight at one end of the latter, means providing for pivotal adjustment of said plates either individually or jointly throughout a predetermined range with respect to said end of the weight, said last mentioned means including means for retaining said plates in their adjusted positions and for restraining the same against rotary displacement with respect to said weight, a member supported by each of said plates, each member comprising a rod-like portion adjustable at will in a straight line with respect to its associated plate, and each member also comprising a vertically extending open helix, said
- 60 10. The combination with a reset weight for a crane limit stop, of a pair of sheet metal plates supported by said weight at one end of the latter, means providing for pivotal adjustment of said plates either individually or jointly throughout a predetermined range with respect to said end of the weight, said last mentioned means including means for retaining said plates in their adjusted positions and for restraining the same against rotary displacement with respect to said weight, a member supported by each of said plates, each member comprising a rod-like portion adjustable at will in a straight line with respect to its associated plate, and each member also comprising a vertically extending open helix, said
- 65 11. The combination with a reset weight for a crane limit stop, of a pair of sheet metal plates supported by said weight at one end of the latter, means providing for pivotal adjustment of said plates either individually or jointly throughout a predetermined range with respect to said end of the weight, said last mentioned means including means for retaining said plates in their adjusted positions and for restraining the same against rotary displacement with respect to said weight, a member supported by each of said plates, each member comprising a rod-like portion adjustable at will in a straight line with respect to its associated plate, and each member also comprising a vertically extending open helix, said
- 70 12. The combination with a reset weight for a crane limit stop, of a pair of sheet metal plates supported by said weight at one end of the latter, means providing for pivotal adjustment of said plates either individually or jointly throughout a predetermined range with respect to said end of the weight, said last mentioned means including means for retaining said plates in their adjusted positions and for restraining the same against rotary displacement with respect to said weight, a member supported by each of said plates, each member comprising a rod-like portion adjustable at will in a straight line with respect to its associated plate, and each member also comprising a vertically extending open helix, said
- 75 13. The combination with a reset weight for a crane limit stop, of a pair of sheet metal plates supported by said weight at one end of the latter, means providing for pivotal adjustment of said plates either individually or jointly throughout a predetermined range with respect to said end of the weight, said last mentioned means including means for retaining said plates in their adjusted positions and for restraining the same against rotary displacement with respect to said weight, a member supported by each of said plates, each member comprising a rod-like portion adjustable at will in a straight line with respect to its associated plate, and each member also comprising a vertically extending open helix, said

helix being adapted to be guided by a cable, and the open form of said helix providing for cooperative positioning thereof about the cable without requiring unreeving of the latter.

6. In combination, a crane limit stop reset weight, a universally adjustable cable guided device for attachment thereto, said device comprising a pair of punched sheet metal plates of like form, each of said plates having formed therein a circular opening to freely accommodate the shank of a bolt supporting the weight and an arcuate slot concentric with said opening, a clamping bolt the shank of which penetrates said arcuate slots when said plates are in assembled relation, said clamping bolt being adapted when tightened relatively to said plates to hold the same in any adjusted positions thereof within the range afforded by the respective slots, associated means for holding said clamping bolt in a substantially fixed position with respect to said weight, a cable guided member carried by each plate, each of said members comprising a relatively long, straight portion lying against one surface of its associated plate, a pair of U-bolts adjustably supported by each plate, the loop portions of each pair of U-bolts being engageable with one of said straight portions to clamp the latter to the plate in any adjusted position of said straight portion, and each of said members also comprising an integral end portion in the form of an open vertical helix, for the purpose set forth.

7. In combination, a crane limit stop reset weight, a universally adjustable cable guided device for attachment thereto, said device comprising a pair of punched sheet metal plates of like form, each of said plates having formed therein a circular opening to freely accommodate the shank of a bolt supporting the weight and an arcuate slot concentric with said opening, a clamping bolt the shank of which penetrates said arcuate slots when said plates are in assembled relation, said clamping bolt being adapted when tightened with respect to said plates to hold the same in any adjusted positions thereof within the range afforded by the respective slots, associated means for holding said clamping bolt in a substantially fixed position with respect to said weight, a cable guided member carried by each plate, each of said members comprising a relatively long, straight portion lying against one surface of its associated plate, a pair of U-bolts adjustably supported by each plate, the loop portions of each pair of U-bolts being engageable with one of said straight portions to clamp the latter to the plate in any adjusted position of said straight portion, each of said members also comprising an integral end portion in the form of an open vertical helix, for the purpose set forth, and each of said plates having at least one hardened steel dowel partially embedded in a surface thereof to be engaged by the straight portion of the respective cable guided member, whereby upon tightening of the U-bolts said dowel will be forced into said straight portion, to insure against turning of the latter relatively to the plate.

8. As an article of manufacture, a universally adjustable cable guided device for attachment to a reset weight of a crane limit stop, said device comprising a pair of punched sheet metal plates of like form, each of said plates having formed therein a circular opening to freely accommodate the shank of a bolt supporting the weight and an arcuate slot concentric with said opening, a clamping bolt the shank of which penetrates said arcuate slots when said plates are in assembled

relation, said clamping bolt being adapted when tightened with respect to said plates to hold the same in any adjusted positions thereof within the range afforded by the respective slots, associated means for holding said clamping bolt in a substantially fixed position with respect to said weight, a cable guided member carried by each plate, each of said members comprising a relatively long, straight portion lying against one surface of its associated plate, a pair of U-bolts adjustably supported by each plate, the loop portions of each pair of U-bolts being engageable with one of said straight portions to clamp the latter to the plate in any adjusted position of said straight portion, each of said members also comprising an integral end portion in the form of an open vertical helix, for the purpose set forth, and each of said plates having a countersunk recess formed in a surface thereof beneath the loop portion of each U-bolt, a hardened steel dowel pin having a lower cylindrical portion and an upper conical portion positioned within each recess, said dowel pins being respectively rigidly secured in position by ring staking the metal of said plate surfaces thereabout, said conical portions projecting a substantial amount beyond said plate surfaces to bite into the straight portions of said members upon tightening of the respective U-bolts, whereby turning of said members relatively to said plates is positively prevented.

9. In combination, a crane limit stop reset weight, an adjustable cable guided device for attachment thereto, said device comprising a pair of supporting plates rotatively adjustable with respect to each other and to the reset weight, a metal member of substantial resiliency supported by each plate, each of said metal members comprising a portion adjustable in a straight line with respect to its associated plate and an end loop portion adapted to surround a cable to be associated therewith, the arrangement being such that said end loop portions may be jointly positioned at any two points within an area of predetermined width completely surrounding the vertical center line of the weight.

10. In combination, a reset weight for a crane limit stop, a universally adjustable cable guided device for attachment thereto, said device comprising a pair of sheet metal members of like form, means for affording a predetermined degree of rotary adjustment of each of said sheet metal members with respect to each other and to the vertical center line of said weight, a resilient steel cable guided member supported by each sheet metal member, each guided member comprising a portion adjustable in a straight line with respect to its associated sheet metal member and an end portion formed to surround a cable to be associated therewith, and associated means for clamping all of said parts in their adjusted positions with respect to each other, said adjustments providing for positioning of said cable surrounding portions jointly at any two points within a complete annular area around the vertical center line of said weight.

11. In combination, a reset weight for a crane limit stop, a universally adjustable cable guided device for attachment thereto, said device comprising a pair of sheet metal members of like form, means for affording a predetermined degree of rotary adjustment of each of said sheet metal members with respect to each other and to the vertical center line of said weight, a resilient steel cable guided member supported by each sheet metal member, each guided member comprising

a portion adjustable in a straight line with respect to its associated sheet metal member and an end portion formed to surround a cable to be associated therewith, associated means for clamping all of said parts in their adjusted positions with respect to each other, said adjustments providing for positioning of said cable surrounding portions jointly at any two points within a complete annular area around the vertical center line of said weight, and each of said cable surrounding portions being in the form of a vertically positioned open helix, whereby the same may be cooperatively assembled with respect to its associated cable without requiring unreeving of the latter.

12. As an article of manufacture, a universally adjustable cable guided device for attachment to a reset weight of a crane limit stop, said device comprising a pair of metal members of like form, each of said members having formed therein a circular opening to accommodate the shank of a bolt supporting the weight and an arcuate slot concentric with said opening, a headed bolt the shank of which extends upwardly through said slots when said members are in assembled position, a nut cooperating with the exposed shank to clamp said members in any adjusted positions thereof within the range afforded by said slots, means associated with said bolt head to hold the same in a substantially fixed position with respect to the weight, a resilient steel cable guided member of circular cross section carried by each of said metal members, each guided member comprising a straight portion, a pair of U-bolts for adjustably clamping said straight portion against one surface of its associated metal member, and each guided member also comprising an end portion in the form of an open vertical helix adapted to surround a cable.

13. As an article of manufacture, a universally adjustable cable guided device for attachment to a reset weight of a crane limit stop, said device comprising a pair of metal members of like form, each of said members having formed therein a circular opening to accommodate the shank of a bolt supporting the weight and an arcuate slot concentric with said opening, a headed bolt the shank of which extends upwardly through said slots when said members are in assembled position, a nut cooperating with the exposed shank to clamp said members in any adjusted positions thereof within the range afforded by said slots, means associated with said bolt head to hold the same in a substantially fixed position with respect to the weight, a resilient steel cable guided member of circular cross section carried by each of said metal members, each guided member comprising a straight portion, a pair of U-bolts for adjustably clamping said straight portion against one surface of its associated metal member, each guided member also comprising an end portion in the form of an open vertical helix adapted to surround a cable, and said guided members being so related to said U-bolts as to provide for assembly of the former in reversed relationship to their respective metal members, whereby said helices may be positioned jointly at any two points within a complete annular area of predetermined width.

14. In combination, a crane limit stop reset weight free to swing pendulumwise adjacent a cable, metal means having an inner end portion attached to said weight and an outer end portion surrounding said cable and engageable with the

latter to resist the swing of said weight, said metal means having an intermediate resilient portion adapted to bend upon initial contact of said surrounding portion with said cable as an incident to swinging movement of said weight, when the pressure of said surrounding portion against said cable is relatively low, and to bend to a substantially greater degree without affecting the resiliency thereof as an incident to the continued swing of said weight, said resilient portion thus acting to effect an increase in the pressure on said cable at a relatively low and substantially uniform rate throughout the swing of said weight in each direction, whereby the energy stored in said swinging weight is dissipated in a manner to minimize the maximum degree of pressure of said surrounding portion upon said cable.

15. In combination, a crane limit stop reset weight free to swing pendulumwise adjacent a pair of cables, metal members respectively having inner end portions attached to said weight and outer end portions surrounding the respective cables and engageable with the latter to resist the swing of said weight, said metal members having intermediate resilient portions respectively adapted to bend upon initial contact of said outer end portions with said cables as an incident to swinging movement of said weight, when the pressure of said surrounding portions against said cables is relatively low, and to bend to a substantially greater degree without affecting the resiliency thereof as an incident to the continued swing of said weight, said resilient portions thus acting to effect an increase in the pressure on said cables at a relatively low and substantially uniform rate throughout the swing of said weight in each direction, whereby the energy stored in said swinging weight is dissipated in a manner to minimize the maximum degree of pressure of said surrounding portions upon said cables.

16. An adjustable cable guided device for use with a reset weight of a crane limit stop, said device comprising an adjustable metal support attached to said weight, a pair of metal cable guided members carried by said support, said guided members being bendable through a relatively great distance without damage thereto, each of said guided members comprising a straight rod-like portion and an end loop portion adapted to surround a cable to be associated therewith, the straight portions of said guided members being adjustable with respect to said support in the direction of their respective lengths, and said metal support being adjustable with respect to said weight to provide for extension of said straight portions from said support at any one of a number of different angles with respect to the vertical axis of the associated weight, whereby said loop portions may be jointly positioned at any two points within an area of predetermined width completely surrounding said vertical axis of said weight.

17. An adjustable cable guided device for attachment to a reset weight of a crane limit stop, said device comprising a pair of supporting plates rotatively adjustable with respect to each other and to the reset weight, a steel cable guided member of substantial resiliency supported by each plate, each of said members comprising a rod-like straight portion adjustable in a straight line with respect to its associated plate and an end portion in the form of an open helix adapted to provide for assembly thereof with respect to a cable without requiring unreeving of the latter,

the arrangement being such that said end portions of said members may be jointly positioned at any two points within an area of predetermined width completely surrounding the vertical center line of the weight, and said cable guided members being tempered to such a degree as to provide for removal of the desired lengths of the outer ends of said straight portions by a hack saw.
